[57] CLAIM

The ornamental design for an automotive wheel, as shown and described.

DESCRIPTION

FIG. 1 is a front view of the automotive wheel of the instant invention;

FIG. 2 is an oblique view of one embodiment of the automotive wheel of the instant invention having a concave configuration;

FIG. 3 is a cross-sectional view of the embodiment shown in FIG. 2 taken along the line 3—3;

FIG. 4 is an oblique view of a second embodiment of the automotive wheel of the instant invention having a convex configuration; and,

FIG. 5 is a cross-sectional view of the embodiment of the automotive wheel shown in FIG. 4 taken along the line 5—5. The broken line showing of environment is for illustrative purposes only and forms no part of the claimed design.
